UNITED STATES PATENT OFFICE

JOSEPH B. HAGAN, OF BERKELEY, CALIFORNIA

DOOR CONTROL

Application filed March 18, 1929. Serial No. 348,015.

The invention relates to means for controlling the opening and closing of doors, and more particularly to the controlling of the operation of garage doors.

5 An object of the invention is to provide means for so positioning and controlling the movement of the ordinary torsion spring, used for closing doors, that such a spring may be utilized, without structural modifications, 10 for urging doors from closed to open position.

Another object of the invention is to provide means of the character described whereby a simple line and pulley arrangement may be utilized to enable a driver of an automobile, while seated therein, to both open and close the doors from a point outside the garage.

Still another object of the invention is to provide a device of the character described 20 which is of simple and inexpensive construction and which may be readily and easily installed.

The invention possesses other objects and features of advantage, some of which, with 25 the foregoing, will be set forth in the following description of the preferred form of the invention which is illustrated in the drawings accompanying and forming part of the specification. It is to be understood, however, that 30 variations in the showing made by the said drawings and description may be adopted within the scope of the invention as set forth in the claims.

Referring to said drawings,

35 Figure 1 is a perspective view of the device of my invention installed on a garage of the double door type, part of the garage being broken away.

40 Figure 2 is an elevation of the actuating spring, showing the position of the spring when the door is closed.

Figure 3 is a view of the spring taken at right angles to the view in Figure 2, the door being in open position.

45 Figure 4 is a fragmentary view of the operating mechanism, showing the means for locking same.

As illustrated in the drawings, the means of my invention are incorporated with a pair of doors 5 and 6 of the garage 7, parts of the

front and side walls 8 and 9, respectively, being indicated.

In the operation of my device, the doors are arranged to be urged to an open position and in the preferred embodiment of the invention I am enabled to use for this purpose, by reason of a novel mounting thereof, torsion spring 12 of the type that is in common use for moving doors to a closed position. Secured on the inside of the front wall 8, 55 and having a portion thereof overlapping the side edge 13 of the opening 14 of the garage is a block 16 to which is secured one of the attaching elements 17 which carries one end of the spring, the element 17 being preferably, as here indicated, positioned on the side-edge 15 of the block lying within the area of the opening. The other end of the spring is carried by an attaching element 18 which is secured to the door adjacent the inner edge 19 thereof. It will be understood 60 from the foregoing that both ends of the spring are positioned to lie within the plane of the opening. 70

Since the spring, as previously explained, 75 is arranged to urge the door to open position, it will be clear that, when the door is in such position, the spring will be disposed in an extended relation, as indicated in Figure 3. However, when the door is moved to closed position, the ends of the spring being anchored to the elements against rotation, the coils will be twisted torsionally whereby sufficient potential energy may be stored up in 80 the spring to urge the return of the door to open position. As will be clear from Figure 85 2, it will be seen that the block extends vertically upward to a point approximately half way up the length of the spring, thus serving to retain the spring in position whereby the twist imparted thereto, during the closing movement of the door, will be expended in rotating the coils rather than in uselessly distending the spring. It will also be seen that

since the block retains the spring in the plane 90 of the opening there will be no danger of the spring entering the crack between the edge of the door and wall and thus interfering 95 with the proper closing of the door. In practice I have found that proper positioning and

operation of the spring may be had by positioning the block so that the edge 15 will lie flush with the inner face of the door when the latter is in open position. Variation in the force of the spring may be effected in the usual manner by turning the rotatable stem 21 of the attaching element 18.

In applying the springs to the doors it will be obvious that the relative positioning of the attaching elements on the door and block will be reversed on one of the double doors, that is while the elements 17 and 18 are respectively positioned on the block and door, with respect to door 5, on applying the spring 15 to the opposite door 6 the elements 17 and 18 will be placed on the door and block respectively.

Means are provided for controlling the opening and closing of the doors, as previously stated, from a point outside the garage. Secured to the doors adjacent their upper outer edges, such as by means of screw-eyes 22 and 23, are flexible lines 24 and 25 respectively, which are secured to a line 27 which passes around a pulley 28 and extends through a conduit 29. The conduit extends to a point outside the garage so that the portion of the line 27 which extends from the conduit may be grasped by the driver of an automobile while seated within the car, to open or close the doors. As will be clear from Figure 1, the line 27 passes around a pulley 31 supported at the end of the conduit, while the free end of the line is provided with a suitable weight 32, the latter being of such heft as to counteract the door opening force of the springs 12. Preferably, the lines 24 and 25 pass through a double pulley 33 fixed to a suitable member such as the beam 34 at the top of the opening 14 of the garage.

In the operation of the device, it will be evident that when the weighted end of the line 27 is raised so as to relieve it of the weight, the doors will, under the action of the springs, proceed to move into open position and, since the weight 32 is not sufficient to completely counteract the force of the springs, the doors will stay in opened position. On the other hand, to close the doors the operator merely pulls on the weighted end of the line so that the doors will be forced against the action of the spring into closed position. Preferably, the portion of the line 27 within the conduit, in that section of the latter lying outside of the garage, is formed of metal link chain, and in order to lock the doors against opening, a padlock 36, or the like, may be placed about one of the links of the chain so as to prevent the unauthorized inward movement of the line in the conduit to effect the opening of the doors.

While I have here shown the weight 32 disposed outside the garage, it will be evident that, if desired, the weight may be hung from a portion of the line 27 inside the garage.

It will now be evident that the device of my invention is well adapted to the accomplishment of the object and purposes of the foregoing.

I claim:

1. In combination with an opening in a wall arranged to be closed by a door, spring means arranged to urge said door from closed to open position, line portions at the inner side of said door and connected thereto, a line connected to said portions and arranged to pass from the inside to outside the wall whereby said door may be closed from a point outside said wall, a weight connected to said line and having a heft overcoming the door opening urge of said spring means. 70

2. In combination with a garage door of the two-door type, springs on each of said doors arranged to urge said doors from closed to open position, line portions on the inside of the garage attached to said doors, a line connected to said portions for opening the doors from a point outside the garage, means providing a passageway from inside to outside of said garage for the slidable reception of said line, pulleys at the inner and outer ends of said last means for the passage of said line thereover, a weight on the line for holding the doors closed against the urge of the springs, and means for locking the line 85 in extended position so that said line may not be manipulated to open the doors. 90

In testimony whereof, I have hereunto set my hand at Oakland, California, this 4th day of March, 1929.

JOSEPH B. HAGAN.
